LOOSE-LEAF BINDER

Howard J. Henderson, Rochester, N. Y., assignor
to Lawyers Cooperative Publishing Company,
Rochester, N. Y., a corporation of New York

Application October 2, 1942, Serial No. 460,505

12 Claims. (Cl. 129—8)

The object of this invention is to make a new and improved type of loose leaf binder.

Another object of the invention is to provide in the binder an assembly bar that is hinged to the back independent of either cover and another assembly bar that is loose and detachable.

Another object of the invention is to provide the hinge bar and the assembly bar each with two pins rigidly attached thereto and standing at right angles thereto on either of which loose leaf sheets that have been suitably perforated can be assembled.

Another object of the invention is to provide the hinged assembly bar with a tube standing perpendicularly thereto and rigidly attached thereto which tube serves as a pin of large diameter for the purpose of engaging with the large perforation in each sheet.

Another object of the invention is to provide a back made with two pieces to one of which the covers are hinged and an auxiliary back having a flange rigid therewith on one side and a flange hinged thereto on the other side, the hinged flange having the two pins of small diameter and the tube attached thereto at right angles to the flange.

Another object of the invention is to provide a small opening in the rigid locking flange and in the loose detachable assembly bar which openings when the binder is closed or the book is shut stand in line with the opening of the tube.

Another object of the invention is to provide a separate loose pin that passes through the small opening in the rigid flange and then through the opening in the detachable assembly bar and into the tube for the purpose of locking the rigid flange on one side of the auxiliary back in a position parallel to the hinged flange on the other side of the back thereby locking the loose sheets in the binder.

Another object of the invention is to hold the loose pin tightly in place by one of the covers when the book is closed.

These and other objects of the invention will be illustrated in the drawings described in the specification and pointed out in the claims at the end thereof.

In the drawings:

Figure 1 is assembly view of the binder with all the parts thereof in place and with one of the covers shown in open position, the loose leaf sheets being omitted therefrom.

Figure 2 is a front elevation of the binder with the covers in closed position looking at it from

the right in Figure 1, the parts being shown on a larger scale than Figure 1.

Figure 3 is a section on the line 3x—3x in Figure 2.

Figure 4 is an assembly view of the binder with the two covers and the back all shown in the same plane and with the loose detachable assembly bar removed with part of the loose sheets assembled thereon, another part of the loose sheets being left assembled on the hinged assembly bar.

Figure 5 is a sectional view through the back of the binder on the line 5x—5x of Figure 2, showing the tube in section with the locking pin inserted therein, it being understood that Figures 2, 3 and 5 are all in the same scale and are shown on a scale larger than Figures 1 and 4.

In the drawings, like reference numerals indicate like parts.

In the drawings reference numeral 1 indicates the back of the binder to which are hinged the covers 2 and 3.

Reference numeral 4 indicates the secondary back which has the flange 5 rigid therewith on the one side and the assembly bar or flange 6 hinged thereto on the other side. The flange 5 is separate from the cover 2 so that the cover 2 can swing independent thereof.

Rigidly attached to the hinged flange or assembly bar 6 are the pins 7 and 8 near the outer ends thereof and the tube 9 at the middle thereof. These parts 7, 8 and 9 stand perpendicular to the hinged assembly bar 6. The rigid flange 5 has one hole 10 therein which hole is substantially the same diameter as the inside diameter on the tube 9.

Loosely associated with the rigid flange 5 is the loose detachable assembly bar 11 shown in Figure 4 in which bar is provided three holes 12, 13 and 14, the hole 13 being in alignment with the hole 10 in the flange 5 and the hole in the tube 9 when the parts are assembled as shown in Figure 1, and the holes 12 and 14 are in line and also engage with the pins 7 and 8 when the parts are assembled as shown in Figure 1.

On the loose assembly bar 11 is provided two pins 15 and 16 rigid therewith which pins are shown in full lines in Figure 2 and in dotted lines in Figure 4. When the book is assembled complete as shown in Figure 1, the pins 7 and 8 extend up through the loose leaves and the pins 15 and 16 extend down through the loose leaves, each and all of these pins extending through all or substantially all of the loose leaves of the book when the book is assembled as shown in

Figure 1 whether the book is full of leaves or only partially full of leaves.

The leaves are assembled in the book in the first instance as shown by opening the book as in Figure 4 and then placing the leaves in their proper order on the pins 7 and 8 and the tube 9 when all the leaves are placed on the pins 7 and 8 in the first instance then the loose assembly bar 11 is placed in proper position with its pins 15 and 16 inserted in the perforations in the leaves, then the back 1 and 4 is swung from the position shown in Figure 4 to the position shown in Figure 1. This brings the rigid locking flange 5 into position over the loose assembly bar 11 and then the locking pin 17 is inserted through the holes 10 and 13 and into the hole in the tube 9, this completes the locking of all the parts together and the assembly of all the parts is complete, and the cover 2 can be swung into place to close the book as shown in Figure 5.

When it is necessary to open the binder for the purpose of removing some sheets or inserting additional sheets, the process of the assembly as above described is reversed as follows:

The cover 2 is swung back to the position shown in Figure 1. The locking pin 17 is removed, the rigid locking flange 5 is swung back to the position shown in Figure 4 and the loose assembly bar 11 is removed and all the sheets that are temporarily to be removed are removed with it while in engagement therewith. This exposes the sheet or sheets that it is desired to be removed which sheet or sheets can then be taken out and others can be inserted in their place and this insertion and removal of sheets can be followed up indefinitely until all the sheets are assembled as may be desired on either the hinged assembly bar 6 or on the loose assembly bar 11. Then the two parts of the book can be brought together so that the pins 15 and 16 engage with the holes 19 and 20 and the pins 7 and 8 engage with the holes 21 and 22 in the loose sheets and the tube 9 engages with the large hole 23 in the loose sheets after which the two parts are fastened together by raising the back to the position shown in Figure 1 and bringing the flange 5 into line and inserting the locking pin 17. Then the cover 2 can be thrown to closed position.

It will also be understood that in making the binder in this way all metal parts can be entirely dispensed with or such parts as may be desired may be made of metal. In the preferred construction the parts 7, 8, 15, 16 and 17 and the tube 9 are made of fiber. The bars 6 and 11 can be of fiber or wood. It being understood that fiber parts are used instead of metal because of priority orders, and it will also be understood that other materials may be substituted for the parts made of fiber.

I claim:

1. In a loose leaf binder the combination of covers and back in one piece, a solid one-piece auxiliary back attached to said first named back, a locking flange on one side of said auxiliary back, a hinged assembly bar on the other side of said auxiliary back, a loose detachable assembly bar on the first named side of said auxiliary back, said loose detachable assembly bar normally placed on the inside of the locking flange, pins on each of said bars extending toward the other bar, said pins engaging with holes in the loose leaves for the purpose of holding the loose

leaves between them, means for fastening the loose assembly bar to the locking flange.

2. In a loose leaf binder the combination of covers and back in one piece, a solid one-piece auxiliary back attached to said first named back, an assembly bar fastened to one side of the auxiliary back, said bar having a tube attached thereto, a locking flange at the other side of the auxiliary back and a loose assembly bar placed adjacent thereto, said flange and said loose bar each having a pin hole therein and a pin capable of being inserted in said holes and in said tube for locking the parts together.

3. In a loose leaf binder the combination of covers and back in one piece, a solid one-piece auxiliary back attached to said first named back, a locking flange on one side of said auxiliary back, a hinged assembly bar on the other side of said auxiliary back, a loose detachable assembly bar having two pins thereon, the locking flange adapted to engage over the loose assembly bar, both said flange and the loose assembly bar having a pin hole therein, a pin for engaging the holes in the flange and bar and locking them together, the pins on the assembly bar holding the bar at a suitable elevation above the hinged assembly bar.

4. In a loose leaf binder the combination of covers and back in one piece, a solid one-piece auxiliary back attached to said first named back, an assembly bar hinged on one side of said auxiliary back, a loose detachable assembly bar placed adjacent to the other side of the said auxiliary back, each of said bars having long pins rigidly fastened thereto and extending close to the other bar and means for fastening the loose assembly bar to the auxiliary back, said fastening means permitting the loose assembly bar to be released from the auxiliary back, loose leaves being adapted to be held between the two bars, by the pins thereon, the loose assembly bar being removable with any portion of the loose leaves.

5. In a loose leaf binder the combination of covers and back in one piece, a solid one-piece auxiliary back attached to said first named back, an assembly bar hinged on one side of said auxiliary back, a loose detachable assembly bar placed adjacent to the other side of the said auxiliary back and a rigid locking flange secured to said other side of the auxiliary back, each of said bars having long pins rigidly fastened thereto and extending close to the other bar, a tube rigidly fastened to the hinged assembly bar, the rigid locking flange and the loose assembly bar each having a hole therein that can be brought into line with the hole in the tube, and a locking pin for locking the flange and the loose assembly bar to the tube.

6. In a loose leaf binder the combination of a rigid back, a flange rigid on one edge of said back, and standing at right angles to the back, a bar hinged on the other edge of said back, said bar being substantially parallel to the flange when the binder is closed, pins fastened to said hinged bar and extending upward towards the flange when the binder is closed, a hollow tube extending up from said bar, said flange having a hole therein placed above the tube when the binder is closed, a pin adapted to pass through the hole in the flange and engage in the tube for the purpose of locking the flange and bar in parallel relation with each other.

7. In a loose leaf binder the combination of a rigid back, a flange rigid on one edge of said back,

and standing at right angles to the back, a bar hinged on the other edge of said back, said bar being substantially parallel to the flange when the binder is closed, pins fastened to said hinged bar and extending upward towards the flange when the binder is closed, a hollow tube extending up from said bar, said flange having a hole therein placed above the tube when the binder is closed, a pin adapted to pass through the hole in the flange and engage in the tube for the purpose of locking the flange and bar in parallel relation with each other, a cover hinged on the rigid back and adapted to cover the pin and hold the pin in place when the cover is closed.

8. In a loose leaf binder the combination of a rigid back, a flange rigid on one edge of said back and standing at right angles thereto, a bar hinged on the other edge of said back, said bar being substantially parallel to the flange when the binder is closed, pins fastened to said hinged bar and extending upward toward the flange when the binder is closed, a loose detachable assembly bar having pins thereon extending towards the hinged bar when the binder is closed, a hollow tube extending up from the hinged bar, said flange and said assembly bar having a hole therein placed above the tube when the binder is closed, a pin adapted to pass through the holes in the flange and in the assembly bar and engage in the tube for the purpose of locking the flange and the assembly bar and the hinged bar in parallel relation with each other.

9. In a loose leaf binder a combination of a rigid back, a flange rigid on one edge of said back and standing at right angles thereto, a bar hinged on the other edge of said back, said bar being substantially parallel to the flange when the binder is closed, pins fastened to said hinged bar and extending upward toward the flange when the binder is closed, a loose detachable assembly bar having pins thereon extending towards the hinged bar when the binder is closed, a hollow tube extending up from the hinged bar, said flange and said assembly bar having a hole therein placed above the tube when the binder is closed, a pin adapted to pass through the holes in the flange and in the assembly bar and engage in the tube for the purpose of locking the flange and the assembly bar and the hinged bar in parallel relation with each other, said assembly bar being adapted to be interposed between the end of the tube and the flange and held in place by the flange.

10. In a loose leaf binder a combination of a rigid back, a flange rigid on one edge of said back and standing at right angles thereto, a bar hinged on the other edge of said back, said bar being substantially parallel to the flange when the binder is closed, pins fastened to said hinged bar and extending upward toward the flange when the binder is closed, a loose detachable assembly bar having pins thereon extending towards the hinged bar when the binder is closed, a hollow tube extending up from the hinged bar, said flange and said assembly bar having a hole therein placed above the tube when the binder is closed, a pin adapted to pass through the holes in the flange and in the assembly bar and engage in the tube for the purpose of locking the flange and the assembly bar and the hinged bar in parallel relation with each other, a cover hinged on the rigid back and adapted to cover the pin and hold the pin in place when the cover is closed.

11. In a loose leaf binder the combination of a rigid back, a flange rigid on one edge of said back and standing at right angles to the back, a bar hinged on the other edge of said back, said bar being substantially parallel to the flange when the binder is closed, a post fastened to the hinged bar, said post extending nearly to the rigid flange, an assembly bar supported by the upper end of the post and held between the post and the rigid flange when the flange and bar are in parallel position, said post being hollow, said rigid flange and assembly bar each having a hole therein centrally with the post, a locking pin passing through the rigid flange and the assembly bar into the hollow post.

12. In a loose leaf binder the combination of a rigid back, a flange rigid on one edge of said back and standing at right angles to the back, a bar hinged on the other edge of said back, said bar being substantially parallel to the flange when the binder is closed, a post fastened to the hinged bar, said post extending nearly to the rigid flange, an assembly bar supported by the upper end of the post and held between the post and the rigid flange when the flange and bar are in parallel position, said post being hollow, said rigid flange and assembly bar each having a hole therein centrally with the post, a locking pin passing through the rigid flange and the assembly bar into the hollow post, said pin having a head thereon resting on top of the rigid flange, a cover adapted to engage said head and hold the pin in place.

HOWARD J. HENDERSON.
